UNITED STATES PATENT OFFICE.

GREEN CLAY GOODLOE, OF WASHINGTON, DISTRICT OF COLUMBIA.

HORSESHOE.

SPECIFICATION forming part of Letters Patent No. 294,990, dated March 11, 1884.

Application filed December 17, 1883. (No model.)

To all whom it may concern:

Be it known that I, GREEN CLAY GOODLOE, a citizen of the United States, residing at Washington, in the District of Columbia, have invented a new and useful Horseshoe, of which the following is a specification.

My invention relates to improvements in horseshoes in which I employ a top or stationary plate of peculiar construction in conjunction with a bottom or removable plate; and it also consists in the novel arrangement and combination of parts, as will be herein-after more fully described, and specifically set forth in the claims. I attain these objects by 15 the mechanism illustrated in the accompanying drawings, in which—

Figure 1 is a perspective view of my improved horseshoe, and Figs. 2 and 3 are views in detail.

Similar letters refer to similar parts throughout the several views.

A represents the part of the horseshoe which is to be permanently attached to the horse's foot. It is made of the usual form for a horseshoe, with grooves *a a* on the under side, in which the heads of the nails are placed. At the toe of the shoe A the parts on each side thereof are cut away to form the projection B, and the heels are also cut away to leave a projection, *b*, as clearly shown in Fig. 2.

C represents the movable part of the horseshoe, formed similar to the upper stationary part, but is formed with a toe-piece, D, having the upwardly-extending portions *d d* fitting and extending upward on each side of the projection B, and between which the projection B on the stationary part is adapted to be

placed. The heel of the movable part C is provided with the pieces *c c*, preferably made integral with the plate or piece C, and project down at right angles with the plane of the piece C, and having the upwardly-extending projections *c' c'* adapted to fit against the heel of the stationary part in the space formed by the projections *b*. The removable part is secured to the stationary part of the shoe by screws, which enter screw-holes *e*, and pass into but not through the upper piece, A, or other suitable means; and it will thus be seen that when the removable part becomes worn or useless it can with but little trouble be removed and a new one substituted. It will also be seen that when the removable part is secured in position it will be effectually prevented from having any lateral or longitudinal movement by means of the projections before described, and the screws will keep it in place.

The movable part may be constructed with blunt toe and heel pieces for summer time, and with sharp edges for winter time.

Having thus fully described my invention, what I claim as new, and desire to secure by Letters Patent, is—

A horseshoe composed of two parts, consisting of the permanent part provided with the projections *B b*, in combination with the removable part, having the toe D, recesses *d d*, and heel-pieces *c'*, adapted to fit in the upper part, and secured thereto by screws, substantially as shown and described.

GREEN CLAY GOODLOE.
